UNITED STATES PATENT OFFICE.

ALBERT T. VAN ALSTYN, OF GRAND RAPIDS, MICHIGAN.

GARTER.

1,313,356.

Specification of Letters Patent.

Patented Aug. 19, 1919.

Application filed May 15, 1916. Serial No. 97,560.

To all whom it may concern:

Be it known that I, ALBERT T. VAN ALSTYN, a citizen of the United States, residing at Grand Rapids, in the county of Kent and State of Michigan, have invented 5 certain new and useful Improvements in Garters, of which the following is a specification.

My invention relates to improvements in 10 garters of that type which are most generally worn by the male sex and encircle the leg just below the knee and attach to the upper end of the sock to hold the latter in position on the wearer's leg.

One object of the present invention resides in providing a garter which, by reason of its simple construction, is extremely 15 inexpensive to produce in small or large quantities, the simplicity residing in the fact that the garter is formed of a single holding length of material.

A further object is to provide a garter which is so constructed that, when in use, the holding tension is distributed from one 20 end of the length of material to the other.

Another object resides in providing a garter comprising a single length or strip of material which, when in use, has a swivel connection at that point where the strip 25 crosses itself, thus forming a fixed length which encircles the leg, thereby preventing sagging; and also this arrangement provides a swivel action for the attaching ends, so that they may be attached to the hose 30 close together or as far apart as may be desirable without affecting, in any way, the band around the leg.

I am aware that it is generally old and well-known to form a garter of a single 35 strip of material which encircles the leg and in which the ends are crossed and attached to the sock or the like to hold the sock and also to maintain the garter strip at the proper tension around the leg. However, such garters have been provided, at 40 the location where the ends cross, with means which permits working sliding adjustment of the overlying ends which is highly unsuccessful due to the fact that the 45 adjustment of the tension about the leg is ever changing and unsatisfactory and permits sagging, and also because of the wear due to the sliding action between the crossed ends at the point of crossing.

Therefore, with the above and other ob-

jects in view, I will now proceed to describe a specific embodiment of my invention which I have shown by way of illustration in the annexed drawing forming a part of this specification and wherein:

Figure 1 is a view, in perspective, of the garter as applied to the leg for the purpose of supporting a sock.

Fig. 2 is a plan view of the crossed ends showing, diagrammatically, the relative positions which they may assume, when the garter is worn, due to the swivel connection.

Fig. 3 is a view in perspective of the garter removed from the leg; and

Fig. 4 is a detail view of one type of 70 swivel connection, in cross-section on the line 4-4 of Fig. 2.

Fig. 5 is a view, in perspective, showing the garter with the attaching ends affixed to the garment in close relation relative to 75 each other, which in no way affects the length of the band around the leg.

In detail:

The garter, as shown, comprises a single length of material designated as a whole by 80 A, and comprising the leg encircling portion 1 and the attaching ends 2 and 3.

Each of the attaching ends 2 and 3 is provided with a garment supporter clasp 4 and 5, respectively, the button and loop type 85 being shown in the illustration, though, in so far as the present invention is concerned any type may be used.

If desired, either the ends 2 and 3 or the leg encircling portion 1 may be constructed 90 to provide for adjustment in any of the usual ways.

At the juncture of the attaching end 2 with the leg encircling portion 1 I provide a snap socket 6 which forms one-half of 95 the separable swivel fastener B and co-acts with the head 7 at the juncture of the leg encircling portion 1 with the attaching end 3, and, when the garter is in use serves to hold the ends 2 and 3 in crossed relation, 100 at the same time permitting, by reason of its swivel construction, the requisite pivotal adjusting movement.

In applying the garter, as shown in Fig. 1, to the leg, the leg encircling portion 1 is 105 passed back of the calf of the leg C and the attaching ends are brought forwardly and crossed as shown and the connection B is snapped to closed relation and thus a complete band of well defined length is 110

formed about the leg. The attaching ends 2 and 3 are then secured to the sock D by means of their respective fasteners 4 and 5 and it will be found that the garter will 5 stay in place and securely hold the sock from sagging.

The garter may also be applied by first attaching one end of the garter to the hose and then winding the garter around the leg 10 and crossing the remaining end over the attached end and affixing said remaining end to the hose at any desired location, then connect the two parts of the swivel attachment B together, thereby forming a complete 15 band around the leg, which aside from elasticity in an elastic garter, has a definite length which will prevent undue sagging of the garter.

It is evident that the leg encircling portion 1 may, if desirable, be made of elastic 20 webbing and the attaching ends 2 and 3 of inelastic webbing; or, the whole length may be made of elastic or inelastic webbing; or, again, the attaching ends may be made of 25 elastic webbing and the leg encircling portion 1 may be inelastic. Also, any means of providing for adjustment may be embodied as, for instance, one or more of the swivel separable fasteners B or an adjusting 30 slide of any type.

While, in the foregoing description and in the drawing, I have set forth a specific embodiment of the present invention, it is nevertheless to be understood that, in practising this invention, I may have recourse to such modifications as fall within the scope 35 of the appended claims.

I claim:

1. A hose supporter comprising in combination a band adapted to surround the leg 40 of the wearer with its end portions crossed, detachable means for uniting the two ends at their intersection in such manner as to prevent relative bodily movement while permitting pivotal movement and a clasp at 45 each of the ends adapted to engage the hose at spaced points.

2. A garter comprising a strip of webbing 50 encircling the leg and crossed, the two ends thereof attaching to the garment to be supported, and swivel means connecting the strip at the crossing point to permit adjustment of the attaching ends without affecting the predetermined normal length of the portion 55 encircling the leg.

3. A garter comprising a strip of elastic 60 webbing encircling the leg and crossed, the two ends thereof attaching to the garment to be supported, and swivel means connecting the strip at the crossing point to permit

adjustment of the attaching ends without affecting the predetermined normal length of the portion encircling the leg.

4. A garter comprising a strip of webbing encircling the leg and crossed, the two ends 65 thereof being formed of elastic and attaching to the garment to be supported, and swivel means connecting the strip at the crossing point to permit adjustment of the attaching ends without affecting the predetermined normal length of the portion encircling the leg.

5. A garter comprising a strip of webbing encircling the leg and crossed, the two ends thereof attaching to the garment to be supported, and separable swivel means connecting the strip at the crossing point to permit adjustment of the attaching ends without 75 affecting the length of the portion encircling the leg.

6. A garter comprising a strip of webbing wrapped once around the limb and crossed, swivel means connecting the two ends of 80 the strip at the point of crossing to form a complete band around the limb, said ends being extended beyond the swivel connection, and a garment attaching means secured to each end.

7. A garter comprising a strip of webbing wrapped once around the limb and crossed, 85 separable swivel means connecting the two ends of the strip at the point of crossing to form a complete band around the limb, said ends being extended beyond the said connection, and a garment attaching means 90 secured to each end.

8. A garter comprising a strip of webbing wrapped once around the limb and crossed, separable swivel means connecting the two 100 ends at the point of crossing to form a complete band around the limb, elastic extensions forming a continuation of each end of said strip, and a garment attaching means secured to each extension.

9. A garter comprising a strip of webbing 105 encircling the leg and crossed, the ends thereof attaching to the garment to be supported, and a pivotal connection having a fixed location with respect to the attaching ends and the portion of strip encircling the 110 leg to permit stretching of the attaching ends without affecting the length encircling the leg.

In testimony whereof I have hereunto set my hand in the presence of two subscribing 115 witnesses.

ALBERT T. VAN ALSTYN.
